UNITED STATES PATENT OFFICE.

HAROLD P. TIPPETT, OF COLUMBUS, OHIO, ASSIGNOR TO THE N. L. HAYDEN COMPANY, OF COLUMBUS, OHIO, A CORPORATION OF OHIO.

METALLIC PACKING.

SPECIFICATION forming part of Letters Patent No. 770,482, dated September 20, 1904.

Application filed May 21, 1904. Serial No. 209,009. (No model.)

To all whom it may concern:

Be it known that I, HAROLD P. TIPPETT, a citizen of the United States, residing at Columbus, in the county of Franklin and State of Ohio, have invented a certain new and useful Improvement in Metallic Packing, of which the following is a specification.

My invention relates to a new and useful improvement in metallic packing.

10 The object of the invention is to provide a packing of this character in which certain difficulties heretofore encountered are overcome. In such packings where segments that interlock have been employed it has been necessary to force said segments into their locking engagement around the rod, and when once they are locked together it is impossible to remove them without breaking the lips or entirely disengaging the segments from the 15 rod. Another great objection to packings employing interlocking tongues is the breaking and crushing of these tongues while the ring is in active service, which greatly decreases the efficiency and life of the packing.

20 Therefore the more essential purposes of my invention are to provide a packing that will obviate the above objections and one that may be readily disengaged from its position around the rod without damaging the segments 25 or disturbing the rod.

Finally, the object of the invention is to provide a device of the character described that will be strong, durable, and efficient and comparatively simple and inexpensive to make and 30 one that will be operative throughout its life.

With the above and other objects in view the invention consists of the novel details of construction and operation, a preferable embodiment of which is described in the specification and illustrated in the drawings, where- 35 in—

Figure 1 is a central vertical sectional view taken through a portion of a cylinder-head, showing the packing therein. Fig. 2 is a view 40 in elevation. Fig. 3 is a detail elevation of one of the segments. Fig. 4 is an inner face view of one of the segments. Fig. 5 is a plan view of the packing-ring.

In the drawings the numeral 1 designates the segments or sections of which the ring 50 is composed. Ordinarily I employ three of these segments; but where packings of considerable diameter are employed more segments may be used. Each segment comprises tongue portions 2 and 3, having inclined ends 4 and 5 substantially parallel to each other. The tongues 2 and 3 terminate at their inner ends at the base of oppositely-extending inclined shoulders 6 and 7. It is to be observed that the segments are cut away on opposite sides to 60 form the tongues 2 and 3 and that the tongues lie on opposite sides of the central diametrical axis of the ring when the segments are assembled. The segments are preferably formed, as shown in the drawings, with the flattened 65 outer faces 8 and rounded edges 9, which terminate flush with the inner faces 10 thereof. When the ring is assembled, two of the segments are placed about the rod 10^a and the third segment pushed into engagement with 70 the first-named segments. It will be readily seen that any one of the segments may be easily disengaged from the others without disturbing the relative position thereof. When assembled, the tongues 2 and 3 overlap 75 each other and the shoulders 6 and 7 register with the inclined ends 4 and 5, thus producing a ring the parts of which are held against lateral displacement, but which are readily movable radially. The packing-ring thus 80 formed is preferably inclosed in a vibrating packing-cup 11, which has a concaved bottom shaped to fit the contour of one of the rounded edges 9 of the ring and fits snugly about the rod 10^a. A follower 12, having a concaved 85 face, engages the opposite rounded edge of the ring and is yieldingly held within the cup and in contact with the ring by means of a coiled spring 13, which fits around the collar 14. The spring 13 rests in an annular recess 90 15, formed in the stuffing-box 16. The cup 11 bears against the shoulder 17 of the gland 18, which is suitably secured to the stuffing-box by means of bolts 19.

The packing-gland and stuffing-box and the 95 cup and follower construction just described

form no particular part of my invention and are employed as a preferable means of supporting the packing-ring in its operative position.

From the above it will be apparent that by 5 disengaging the bolts 19 from the stuffing-box 13 and moving the gland 18 along the rod 10^a, then slipping the cup 11 also along the rod, the packing-ring is exposed and any one of its segments may be readily removed without 10 disturbing the relative position of the rod, which has heretofore been necessary in order to remove the ring or the segments thereof, as where the segments interlock they could not be disengaged without breaking the locking-tongues or sliding the rod out of engagement with the ring.

Another advantage gained by the construction herein set forth is the obliterating of the locking-tongues, which have generally been 20 made small and comparatively thin and easily broken, thereby decreasing the efficiency of the packing.

Having now fully described my invention, what I claim, and desire to secure by Letters Patent, is—

In a metallic packing, the combination with a yieldable supporting means, of a packing-ring comprising segments having curved faces, each segment comprising the tongue 2 having the inclined end 4 and the inclined shoulder 7 30 extending outwardly at a diverging angle to the end 4 and formed at its opposite end with the oppositely-disposed tongue 3 having the inclined face adapted to register with the inclined shoulder 7 and the inclined shoulder 6 35 adapted to register with the end 4 when the segments are assembled, the end 4 and the shoulder 6 extending entirely across the segment.

HAROLD P. TIPPETT.
